UNITED STATES PATENT OFFICE

GARNET P. GRANT, OF LONG ISLAND CITY, NEW YORK, ASSIGNOR TO AUTOSALES CORPORATION, OF LONG ISLAND CITY, N. Y., A CORPORATION OF NEW YORK

DESIGN FOR A GOODS-VENDING DISPLAY STAND

Application filed August 22, 1929. Serial No. 32,508. Term of patent 3½ years.

To all whom it may concern:

Be it known that I, GARNET P. GRANT, a subject of the King of Great Britain, residing at Long Island City, in the county of Queens and State of New York, have invented a new, original, and ornamental Design for Goods-Vending Display Stand, of which the following is a specification, reference being had to the accompanying drawing, forming part hereof.

The drawing is a perspective showing the display stand. The opposite side of the display stand is substantially the same as shown in the drawing.

I claim:

The ornamental design for a goods vending display stand, as shown and described.

GARNET P. GRANT.
